Ernest F. Davis,

UNITED STATES PATENT OFFICE.

ERNEST F. DAVIS, OF NOANK, CONNECTICUT.

WRENCH.

SPECIFICATION forming part of Letters Patent No. 740,251, dated September 29, 1903.

Application filed June 17, 1903. Serial No. 161,899. (No model.)

To all whom it may concern:

Be it known that I, ERNEST F. DAVIS, a citizen of the United States, residing at Noank, in the county of New London and State of Connecticut, have invented new and useful Improvements in Wrenches, of which the following is a specification.

My invention relates to wrenches; and the primary object thereof is to provide a new and useful device of this character capable of having a double adjustment, one a quick and primary, the other a more accurate and secondary, to permit of and insure a rigid engagement of the nut by a wrench.

15 A further object of the invention is to provide a wrench which is cheap of construction, durable, efficient, and quick in operation.

The invention consists in the construction, combination, and arrangement of parts hereinafter fully described, claimed, and illustrated in the accompanying drawings, in which—

Figure 1 is a side elevation of a wrench constructed in accordance with my invention. 25 Fig. 2 is a similar view, the sliding jaw and carriage being in longitudinal section. Fig. 3 is a top plan view thereof. Fig. 4 is a detail perspective view of the carriage. Fig. 5 is a similar view of the dog.

30 Referring to the drawings by numerals of reference, 1 designates a shank, preferably rectangular in cross-section and having one end thereof provided with a rigid jaw 2, the opposite end terminating in a handle 3. The 35 upper edge of the shank is provided for a portion of its length with a rack 4. Mounted upon the shank, to have a sliding adjustment thereon, is a movable jaw 5, the same being of the usual form and construction and provided with a vertically-disposed ear 6, which is formed with a screw-threaded and longitudinally-arranged aperture 7.

8 designates a carriage slidably mounted upon the shank in rear of the sliding jaw, consisting of a rectangular sleeve provided with vertically-disposed flanges 9 and 10, having a seat 12 therebetween. The carriage is connected to the sliding jaw to permit of the adjustment of the latter by means of threaded 45 bolt 13, which is mounted in the aperture 7 and has its opposite end resting upon a recessed bearing 13^a in the upper end of the flange 9

and formed with a milled head 14, occupying the seat 12, to prevent the longitudinal displacement of the bolt from the bearing 13^a. 55 It will be seen that by causing the bolt to rotate by means of the head 14 the jaw 5 will be caused to approach and recede from the jaw 2. The flange 10 has its outer face provided with a dovetail groove 15, in which is 60 mounted, to have a vertical movement, a dovetail dog 16, adapted to engage the rack to hold the carriage in its adjusted position. The dog has the upper end thereof provided with a horizontally-disposed finger-grip 17, 65 formed integral therewith, and by means of which the dog may be lifted from the rack to permit of the carriage being adjusted. To hold the dog normally in engagement with the rack, I provide a leaf-spring 18, which 70 has one end thereof secured to the inner face of the flange 10 and its opposite end carried above the flange and bent to contact with the upper end of the dog. This spring permits the carriage being moved toward the jaw 2 75 to adjust the sliding jaw, but prevents an unauthorized reverse movement.

The object of providing this double adjustment of the sliding jaw is to permit of a quick primary adjustment to the approximate size 80 of a nut and then a secondary and more accurate adjustment, whereby all liability of a proper adjustment not being obtained is obviated.

85 The operation of the wrench may be explained in the following manner: The primary adjustment of the sliding jaw may be obtained by grasping the carriage and sliding it forward upon the shank. After the adjustment if it be found that the nut is not securely gripped the secondary adjustment may be resorted to, which is obtained by causing the bolt 13 to rotate through medium of the head 14.

Having thus described the invention, what 95 is claimed as new is—

A wrench comprising a shank having a rack and rigid jaw, a sliding jaw mounted thereon and provided with a screw-threaded apertured ear, a carriage mounted upon the shank 100 in rear of the sliding jaw, said carriage being provided with flanges providing a seat therebetween and one of which is provided with a recessed bearing and the other with a dove-

tail groove, a screw-threaded bolt adapted to have one of its ends received by the screw-threaded aperture and its other end journaled in the recessed bearing, a milled head to one end of the bolt and adapted to occupy the seat to prevent the displacement of the bolt and to permit of its being rotated, a dovetail dog adapted to be received by said groove and provided with a horizontally-disposed finger-grip formed integral therewith, and a

spring secured to the grooved flange and having its upper end bent to contact with the upper end of the dog.

In testimony whereof I affix my signature in presence of two witnesses.

ERNEST F. DAVIS.
